UNITED STATES PATENT OFFICE

2,589,350

ROTARY CYLINDER HEAT EXCHANGER
WITH SCRAPER

Raymond S. Edmunds, Jr., San Antonio, Tex.

Application September 8, 1949, Serial No. 114,511

1 Claim. (Cl. 257—84)

1

This invention relates to a machine for heating or chilling liquids.

In the processing of fluid dairy products it is desirable that the materials be heated quickly and cooled quickly so that harmful bacterial action in the product may be controlled. It is, therefore, an object of this invention to provide a heat exchange device which can be used to either heat or chill the materials to the desired temperatures in a continuous process.

In the processing of oleomargarine it is desirable that the material be reduced to a relatively cool temperature below its normal melting point from its liquid emulsion state so that the product will congeal and may be worked and formed of convenient shapes and sizes for packaging. It is, therefore, an object of this invention to provide a heat exchange device which can be used to reduce the temperature of liquid margarine emulsion to the desired temperature and simultaneously work the cooled emulsion in a continuous process.

Another object of this invention is to provide an improved rotor engaging in a cylinder and having scraping blades mounted thereon in a manner whereby the adhering material will be scraped from the cylinder, and the blades being arranged in staggered relation along the length of the rotor will subject the material to be worked and mixed into a homogeneous mass.

Another object of this invention is to provide an improved rotor having scraping blades which will be centrifugally held in contact with the surface of the cylinder, the blades being loosely mounted in slots formed in the rotor which are of such shape that the rotor can be easily inserted into the cylinder from one end by swinging the blades radially inwardly into substantial contact with the inner sides of the slots.

Another object of this invention is to provide an improved rotor having scraping blades which are easily inserted onto the rotor and which are prevented from moving out of proper position and jamming between rotor and cylinder when rotor is engaged but motionless in cylinder by the proximity of the inner cylinder wall to the rotor.

Another object of this invention is to provide an improved mounting for the rotor.

With the above and other objects in view, my invention consists in the arrangement, combination and details of construction disclosed in the drawings and specifications, and then more particularly pointed out in the appended claim.

In the drawings,

2

Figure 1 is a detail end elevation of a chilling machine constructed according to an embodiment of this invention.

Figure 2 is a sectional view taken on the line 5 2—2 of either Figure 1 or 3,

Figure 3 is a sectional view taken on the line 3—3 of Figure 2,

Figure 4 is a detail side elevation of the device, Figure 5 is a detail side elevation, partly broken 10 away, of the rotary element embodied in this invention,

Figure 6 is a sectional view taken on the line 6—6 of Figure 2,

Figure 7 is a fragmentary transverse section 15 showing the scraper blade mounting,

Figure 8 is a view similar to Figure 7, showing a modified form of rotor,

Figure 9 is a fragmentary transverse section 20 showing another form of scraper blade and a modified form of rotor constructed according to an embodiment of this invention.

Referring to the drawings, the numeral 10 designates generally a cylinder which is adapted to be disposed in a horizontal position, and has 25 secured to the opposite ends thereof heads 11 and 12. The cylinder 10 has rotatably mounted therein a rotor generally designated as 14 which is formed of an elongated round body 15 having extending from the opposite ends thereof stub 30 shafts 13 and 16.

The body 15 is formed with a plurality of longitudinally extending circumferentially spaced apart slots 17 within which scraper blades 18 are 35 adapted to be loosely mounted. The slots 17 are substantially tangentially arranged so that the scraper blades 18 will be disposed on substantially a tangent to the circle of the inner surface of cylinder 10. By providing the slots 17 the blades 18 may be mounted in these slots of

40 the body 15, and the assembly then inserted into the cylinder 10 from one end thereof. When the rotor is inserted initially into the cylinder 10, the blades 18 are rocked inwardly with the inner edges as a fulcrum, and at this time they will 45 freely pass into the cylinder 10.

The rotor 14 is rotated at a relatively rapid rate so that the blades 18 will be centrifugally forced outwardly into scraping contact with the inner surface of cylinder 10. Preferably, as 50 shown in Figure 5, the blades are arranged in a staggered series so that these blades will serve as a mixing means to mix the material into a homogeneous mass.

The shafts 13 and 16 are journaled in bearing 55 heads 19 and 20, respectively, which are secured

to the heads 11 and 12 by fastening means 21. The bearing heads 19 and 20 engage about the stub shafts 13 and 16 at a point outwardly from packing and sealing glands 22 and 23 which are carried by the end members 11 and 12 respectively. By providing the sealing glands inwardly of the bearings the lubricant used for lubricating the bearings 19 and 20 will be held against contact with any of the liquid material which is passing through the cylinder 10.

The body 15 of the rotor 14 is disposed in a position spaced slightly from the inner surface of the cylinder 10, as indicated at 24, thereby providing a restricted passageway through which the material is adapted to pass. The head 12 has secured thereto an intake pipe 25 for conducting the liquid material into the cylinder 10 at one end thereof, and at one end to the rotor 14 which is spaced from the inner side of the head 12, to provide an intake chamber 26. The material is exhausted from the cylinder 10 at the opposite end thereof, being exhausted through outlet pipe 27 communicating with end chamber 28 formed between the head 11 and the adjacent end of the rotor 14.

In order to provide a means whereby a heat exchange medium may be circulated around the material to be heated or cooled, I have provided a heat exchanging chamber 29 which is formed by positioning an inner jacket 30 about the cylinder 10. An outer jacket 31 is disposed concentrically about the inner jacket 30 and is heat insulated therefrom by heat insulating means 32. The two jackets 30 and 31 are secured to end members or heads 33 which are disposed about the cylinder 10 adjacent the opposite ends thereof and which are adapted to be sealed in any suitable manner with respect to the cylinder 10.

The heat insulating casing formed by the jackets 30 and 31 and the insulating means 32 is communicated with a heat exchange medium by means of inlet pipe 34 which is adapted to be connected to a source of the heat exchange medium, and an outlet pipe 35 returns the heat exchange medium to the supply source.

Referring now to Figure 8 there is disclosed a modified form of rotor embodying a hollow rotor member 14a which is formed with longitudinal V-shaped channels 17a. Scraper blades 18a are loosely mounted in the channels 17a and are centrifugally forced outwardly upon rotation of the rotor 14a. It will be understood that a driving motor or driving member such as a pulley or the like may be secured to stub shaft 16 for rotating the rotor 14 at a predetermined speed of rotation.

Referring to Figure 9 there is disclosed another form of rotor embodying a hollow rotor member 14b which is formed with longitudinal rectangular slots 17b. Scraper blades 18b are loosely mounted in the channels 17b and are free to swing radially inward to permit easy insertion of rotor into cylinder and centrifugally outward to make scraping contact with the inner surface of cylinder 10.

The blades 18b are formed with V-shaped outer scraping edges 36 so that these blades can be

inverted when inserted into the slots 17b so that these blades cannot be incorrectly inserted.

In the use and operation of this device, the material, such as liquid oleomargarine emulsion, is discharged under pressure into the intake chamber 26 of cylinder 10. As rotor 14 rotates in the cylinder 10 and as the material passes lengthwise through space 24 between rotor 14 and cylinder 10, the scraper blades 18 will scrape the adhering material on the inner surface of cylinder 10 and will mix the material into a homogeneous mass. The material is forced under pressure through space 24 and is discharged through outlet pipe 27. A cooling medium is circulated through cooling chamber 29 through intake pipe 34 and exhausting through outlet pipe 35. With a structure as hereinbefore described, the material, such as oleomargarine, may be chilled in a continuous operation and may be kept in a sanitary condition through the medium of the inner packing glands 22 and 23 which are positioned inwardly from the bearings 19 and 20.

I do not mean to confine myself to the exact details of construction herein disclosed, but claim all variations falling within the purview of the appended claim.

What I claim is:

In a heat exchange means comprising a cylinder, a rotor in said cylinder and of lesser diameter to provide a fluid passage between said rotor and said cylinder, said rotor being formed with a series of staggered longitudinally extending slots, each inclined to the radii of said rotor in the direction of rotation thereof and each being divergent in the direction of the open end thereof and having an arcuate closed end, a blade loosely mounted in each slot and extending the full length thereof, the thickness of each blade being substantially equal to the width of the slot at its base and the base of each blade being arcuate conforming to the arcuate closed end of its associated slot to permit operating thereof under the influence of centrifugal force whereby the blade edge may engage the inner wall of said cylinder to scrape the same when the rotor is activated, and inlet and outlet means for said cylinder, said blade edge comprising a straight side and an inclined side, the inclined side being positioned away from the direction of rotation of said rotor.

RAYMOND S. EDMUND, JR.
